COLLAPSIBLE FLUID CONTAINER

Edwin H. Land, Cambridge, Mass., assignor to
 Polaroid Corporation, Cambridge, Mass., a corporation of Delaware

Application March 7, 1946, Serial No. 652,612

5 Claims. (Cl. 222—107)

1

This invention relates to fluid containers and more particularly to containers adapted to contain a fluid composition suitable, for example, for use in a process of forming positive photographic prints.

One of the objects of the invention is to provide a container for releasably containing a liquid suitable for forming a positive photographic print in conjunction with associated materials.

Another object is to provide a liquid-carrying container substantially impervious to said liquid and to oxygen.

A further object is to provide a fluid-carrying container having pliable walls and differential sealing means adjacent edge portions thereof whereby said liquid may be directionally released when the container is subjected to compression.

Still another object is to provide a collapsible liquid-carrying container formed from a pliable sheet material, said container being suitable for attachment to a material adapted either to carry or to otherwise serve in the formation of a positive photographic print.

A still further object is to provide a collapsible container releasably enclosing a viscous liquid, said container being formed from pliable and deformable materials and being suitable for positioning between sheet materials comprising a photosensitive film and a material for carrying a positive photographic print whereby said liquid may be released between said sheet materials and serve to form said print when the aforesaid container is subjected to compression.

Yet another object is to provide a collapsible container releasably carrying a predetermined quantity of a liquid suitable for release to an adjacent photographically exposed film whereby a positive print of the subject image of said film may be formed.

Yet a further object is to provide a collapsible container releasably carrying a liquid suitable for processing a photographically exposed photosensitive film, for transporting an image-forming component to a material for carrying a positive print of the subject image of said film, and for forming said positive print.

Other objects of the invention will in part be obvious and will in part appear elsewhere.

The invention accordingly comprises the products possessing the features, properties, and rela-

2

tion of components which are exemplified in the following detailed disclosure, and the scope of the application of which will be indicated in the claims.

5 In the drawings, wherein like reference characters refer to like parts throughout the several views:

Fig. 1 is a perspective view of one form of liquid container prior to introduction of a liquid 10 thereinto and subsequent closure of container walls;

Fig. 2 is a cross-sectional view comprising the 15 liquid container of Fig. 1 after introduction of a liquid and closure of container walls, the container being shown mounted on a carrying material;

Fig. 3 is a perspective view of a modification of the container of Fig. 1;

Fig. 4 is a cross-sectional view comprising the 20 container of Fig. 3, after introduction of a liquid and closure of container walls, the container being embodied in a sheet material;

Fig. 5 is a cross-sectional view of a modification 25 of the liquid-carrying container of Fig. 4 similarly embodied in a sheet material; and

Fig. 6 is a perspective view of a composite assembly comprising the container of Fig. 1, having a liquid sealed therein, mounted on a sheet material suitable for use in forming a positive 30 photographic print.

Referring to Fig. 1, a form of fluid container comprehended by the invention is illustrated, said container being constructed of a multi-layer, preferably medially folded material comprising walls 12 and 14, said individual walls being formed by medial fold 16. A surface portion of one of said walls as, for example, portion 18 of wall 14, is suitable for receiving and in part confining said fluid and a substantially equal surface portion of the other of said walls as, for example, surface portion 19 of wall 12 is suitable for further confining said fluid upon closure of said walls. A composition of fluid particularly adapted to introduction to the container shown is one 40 having a high viscosity, said characteristic of the fluid tending to prevent its escape prior to closure and sealing of said container.

The aforesaid fluid container is preferably constructed of an oxygen impermeable sheet material and, more particularly, of a metal foil such

as a sheet of lead foil 20 as, for example, a sheet of said lead foil .001 inch in thickness and having other dimensions predetermined according to intended use, said use comprising association of the container with a photosensitive film of predetermined dimensions. One surface of said sheet material is preferably coated with a material 22 substantially impervious to the fluid composition to be enclosed as, for example, with a film comprising a polyvinyl acetal such as polyvinyl acetal or polyvinyl butyral. More particularly adapted to serve as a coating for said surface is a mixture of 60-72% polyvinyl butyral, 10-23% $\frac{1}{2}$ -second nitrocellulose, and approximately 5% of dibutyl sebacate. The outer or noncoated surface of the aforesaid sheet of lead foil may preferably be laminated to a sheet material 26 as, for example, to a craft paper or scrim material for limiting deformation of container walls. A suitable composite sheet material for forming said container comprises a layer of lead foil, a layer comprising a mixture of polyvinyl butyral and other ingredients, above described, and a layer of craft paper.

In the completed, closed, liquid-carrying container, the aforesaid coating serves both to substantially prevent direct contact of the carried fluid with said lead foil and as a means for bonding together facing marginal portions of said coated material bordering the enclosed liquid, when, for example, said portions are subjected to an application of heat and/or pressure, said portions, thus bonded, providing means for sealing said liquid within the container. A second coating 24 of a material such as ethyl cellulose or an ethyl cellulose and paraffin mixture overlayed on a marginal portion of said first-named coating 22, when bonded to a facing marginal portion having said coating 22 thereon, serves as a means for bonding said facing marginal portions differentially with respect to other facing marginal portions having solely coating 22 thereon.

Upon closure of said walls 12 and 14, marginal surface portions 28, 30 and 32 come in contact with marginal surface portions 28a, 30a, and 32a, respectively, and may be suitably bonded together and when thus bonded, provide, in conjunction with fold 16, means for effecting a completely sealed enclosure or space. The aforesaid materials and constructions provide a container capable of substantially confining a liquid as, for example, a liquid adapted to the processing of a photographically exposed photosensitive film and to the forming of a positive photographic print in conjunction therewith, said container effectively preventing loss of liquid content due to exudation, absorption, or evaporation thereof, and acting to preserve said liquid substantially free from oxidation, it being understood that the liquid may be introduced to the container in an inert atmosphere.

In the cross-sectional drawing of Fig. 2, the container of Fig. 1 is shown carrying a liquid 34 as, for example, a viscous liquid adapted to the aforementioned photographic function, said container having wall 12 folded to extreme position with respect to wall 14 and having wall marginal surface portions sealed, as above described, said sealing of marginal surface portions 30 and 30a being illustrated, and the layer type construction of container walls shown in Fig. 1 being understood to exist although not delineated. The liquid, as shown, preferably substantially fills the space between said walls, thereby further precluding the presence of oxygen within the container.

The container is represented as attached by means of adhesive material 36 to a strip of sheet material 38, for example, to a material suitable for serving as a carrier for the container where propulsion of said container is required in ultimate use, and which may likewise serve, in conjunction with the aforesaid photographically exposed film, as a carrying material for a positive print when the liquid in the container is released thereto and to said film. An adhesive material suitable for effecting said attachment of container and carrying strip is polyvinyl acetate in solution.

The aforementioned constructions and materials of the liquid-carrying container are such that, in use, the contained liquid may be released in a predetermined manner upon an application of compressive stress to the container walls as, for example, by superposing a second strip of sheet material upon the assembly of container and carrying material shown in Fig. 2, and passing said superposed materials between pressure rollers in a predetermined direction. Upon said application of compression, the container is adapted to release of said contained liquid between marginal surface portions 30 and 30a for the reason that overlaid coating 24 (Fig. 1) of said portion 30 of lower wall 14 bonded to coating 22 of said portion 30a of upper wall 12, comprising the bonding of differential coatings, provides a relatively weaker bond than that existing between bonded marginal surface portions 28-28a and 32-32a having identical coatings thereon. It is likewise to be understood that fold 16 and other wall portions are less susceptible to fracture than are said marginal surface portions 30-30a to separation.

It will be apparent that alternative but functionally similar means for providing differential adhesion of marginal surface portions of a container, or for providing a portion thereof prone to fracture or separation, may be employed for obtaining directional release of a contained liquid, said means being suitable for use in conjunction with compression applied to said container. Such alternative means may comprise a greater width of marginal surface portions 28-28a and 32-32a than that of marginal surface portions 30-30a, said relative dimensions permitting the use of coatings having similar adhesive properties on all said portions. Further modifications comprise the insertion of a strip of material as, for example, a strip of cellulose acetate between marginal surface portions 30-30a, or, for example, the employment of facing marginal surface portions of substantially equal width bonded together under the influence of differential applications of heat and pressure.

The container shown in Fig. 3 is a modification of that illustrated in Fig. 1 and comprises walls 39 and 40 formed by medial fold 42, said wall 40 having a concave portion or recess 44 embossed therein and said recess being adapted to the reception and partial confinement of a liquid. A planar area 46 of wall 39 substantially equal to the planar dimensions of said recess is adapted to effect further confinement of said liquid upon closure of said walls. The materials, constructions and functions of said container may in all other respects be similar to those above-described with respect to the container of Fig. 1.

In the cross-sectional drawing of Fig. 4, the container of Fig. 3 is shown carrying a liquid 48 as, for example, a viscous liquid of the type previously described, said container having wall 39 folded to extreme position with respect to wall 40

and having wall marginal surface portions sealed in the aforementioned manner, said relatively weaker bonded marginal surface portions forming liquid release area 50 being illustrated, and the layer type construction of container walls shown in Fig. 3 being understood to exist although not delineated. The container is represented as attached by means of an adhesive material 52 to a strip of sheet material 54, said adhesive and sheet material being similar to adhesive 36 and carrying material 38 shown in Fig. 2. It will be noted that the recessed portion of container wall 40 lies within a similarly embossed recessed portion of sheet material 54, said last-named material thus providing, in effect, a reinforcing wall portion contiguous said wall 40.

Fig. 5 represents, cross-sectionally, a modification of the container illustrated in Fig. 4 wherein walls 56 and 58 are formed from two separate sheets of multilayer material of the type described relative to Fig. 3, bonded marginal surface portions 60 thus supplanting the fold previously shown, where a single folded sheet was employed. It will be understood that marginal surface portions 62 are less firmly bonded than said portions 60 whereby directional release of contained liquid 64 between said portions 62 may be obtained by an application of compression to said container walls, as previously described.

With reference to Fig. 6, a substantially longitudinal view of an assembly comprising a plurality of containers 66 and 68 of the type shown in Figs. 1 and 2 and the arrangement of said containers on a fragmentary length of carrying material suitable for the reception of a positive photographic image as, for example, a paper material 70, having a surface coating of baryta and lead acetate, to which said containers are attached, is shown. It will be noted that an area 72 of said coated paper material lies adjacent container 66, said area being suitable for receiving the released liquid of container 66 and for carrying a photographic print of similar dimensions to a photographically exposed frame of film with which the assembly is designed for use, in superposed relationship, in forming said positive print. Adjacent area 72 is an area 74 of said paper material suitable for use in trapping any excess of liquid which may pass beyond area 72, one form of said liquid-trapping means being shown and comprising a plurality of perforations 76 in said paper material through which said liquid may pass to an absorbent material 78, such as a strip of blotting paper attached to the under side of paper material 70. Container 68 is a counterpart of container 66 and the liquid therein is designated for release to area 80 of the paper material, said area, shown in part only, being intended for use with a second frame of exposed film for forming a second positive print of the subject image thereof. In accordance with the aforesaid function of elements, it will be apparent that said containers are spaced at predetermined longitudinal intervals of print-carrying material 70, a given container, in the form of assembly shown, having wall 14 thereof attached to said carrying material in a manner whereby a long dimension of the container lies transverse of the carrying material and the aforesaid relatively weaker bonded marginal surface portions 30, 30a are adjacent print area 72. Visible marginal areas 82, 84, and 86, surrounding the liquid-carrying portion of the container on three sides, represent those surface portions of container wall 12 to which heat and/or pressure have been directly applied to provide the aforementioned bonding of

facing marginal surface portions shown in Fig. 1, the fourth side adjacent said liquid-carrying portion being formed by medial fold 42 and requiring no sealing.

5 In use, it is contemplated that the visible portions of the assembly of Fig. 6 are to be superposed with a photosensitive film more particularly in a manner whereby photographically exposed frames of said film are superposed, respectively, 10 with areas 72 and 80 of material 70. It is further to be understood that said photosensitive film and assembly, in facing relationship, are to be subjected at least to compressive force for obtaining release and spreading of the container-carried liquid over said superposed film frames and areas 15 72 and 80, and that any excess of said liquid is to be received and substantially confined by trapping means 74. Said assembly, either in conjunction with a separate, superposed photographic film of the aforesaid type, or attached to a photosensitive film, exposable, for example, through its base material, and thus forming a composite assembly, is adapted to use either in a photographic darkroom, or in a novel camera apparatus such as that described in my copending application, Serial No. 578,379, filed February 17, 1945 (now abandoned and replaced by application Serial No. 64,870, filed December 11, 1948, and issued as Patent No. 2,543,181 on February 27, 20 1951), wherein said film and assembly, as shown, 25 may be subjected to compressive and propulsive forces as, for example, between pressure rollers, said assembly being adapted to insertion between said rollers at left-hand extremity 88 and to propulsion therebetween from left to right.

30 It will be understood that both the form and capacity of the container and the dimensions and surfacing composition of the materials over which said liquid is to be spread are predetermined relative both to each other and to the compressive 35 properties of pressure rollers or other suitable means for imparting compression. The supply of said liquid carried by a given container may, for example, be in excess of the minimum quantity required for coverage of adjacent areas of film and print-carrier material to insure complete coverage thereof under conditions most favorable to the spreading of said liquid. Said liquid may 40 preferably be provided in a quantity sufficient at least for obtaining adequate coverage of said areas under conditions of contemplated use least favorable to the spreading procedure as, for example, under conditions where a relatively low temperature would impede the flow of said liquid and where the compressive properties of pressure 45 rollers would be lessened by reason of their rotation at excessive speeds. It will thus be obvious that said excess portion of contained liquid is supplied in a quantity dependent upon influences 50 of predetermined magnitude unfavorable to said 55 liquid-spreading process.

60 The adhesive properties of said liquid interposed between said film and print-carrier materials, under compression, are such as to provide a lamination of said materials which is maintained after relief of said compressive force therefrom. Where said materials are substantially opaque and inasmuch as an inner surface of said materials carries the positive print, or where formation of a transparency is intended and one of 65 said materials is substantially opaque, it will be apparent that separation of said materials is required for viewing the completed print. Accordingly, the adhesive properties of said interposed liquid or of an interposed film-like coating derived 70 from an ingredient of said liquid are prede-

terminated for permitting the separation of said materials upon completion of the formation of said positive print.

Referring to Fig. 6, after formation of a positive print upon surface area 72, severance of exhausted container 66 and liquid-trapping portion 74 therefrom may be obtained, transverse areas 90 and 92 being provided for the purpose and said areas being adapted to the application thereto of severance means or containing, for example, semi-perforations which permit manual separation of said surface area 72 from said adjacent portions.

The liquid releasably carried by the aforesaid containers is of a composition comprising materials for developing a latent image in a photographically exposed photosensitive layer of a film, for providing an image-forming component therein, and for transporting said component to a receiving material whereby a positive print of the subject image of said exposed layer may be formed. Said receiving layer may comprise either the print-carrier material 78 of Fig. 6 or a film-like coating formed on said material by an ingredient of said liquid. The degree of viscosity of the aforesaid liquid is established according to the included quantity of at least an ingredient contributing thereto as, for example, of said film-forming ingredient.

A liquid composition suitable for the above-described photographic purposes may, for example, comprise 200 cc. of water, 9 g. of sodium sulfite, 8.75 g. of sodium hydroxide, 21.31 g. of sodium carboxymethyl cellulose, 9 g. of hydroquinone, and 5 g. of sodium thiosulfate, it being understood that said composition is presented in an illustrative sense only and that the invention is not limited to the aforesaid materials or proportions, as set forth. For image areas of film and print-carrier material of approximately $2\frac{1}{4} \times 3\frac{1}{4}$ inches, .35 g. to .5 g. of the above-formulated liquid is capable of providing a coating therebetween .0001" in thickness and slightly more than .1 g. in weight, and is sufficient to form a positive print within or upon said coating.

There is thus provided a novel container for a liquid adapted, upon application of mechanical stress thereto, to release the contents thereof in a predetermined direction, said container being impervious to said liquid and to the vapor of said liquid. The container is preferably formed of a multilayer composite material comprising as an inner layer, i. e., as the layer in contact with the liquid contents of the container, a material which is impervious to the liquid, and as a second layer a substance which is impervious to the vapor of said liquid and which is protected against reaction with said liquid by said first layer. Where the liquid content of the container is to be an alkaline solution such as the photographic composition hereinbefore described, the container is preferably formed of a composite material whose inner layer is a film which is not hydrolyzed by the composition or a film which undergoes an initial hydrolysis upon contact with the liquid, but whose film-forming properties and impermeability to the liquid are not adversely affected by such hydrolysis. Accordingly, in its preferred form the present invention comprises a container formed of a multilayer material whose inner layer is formed of a plastic such as a polyvinyl butyral composition which is substantially inert to an alkaline solution, said layer being backed by a metal foil which is impervious to the vapors of said solution. Although plastics such as the polyvinyl acetals of the type which undergo no hydrolysis

are preferred materials for the inner coating, it is to be expressly understood that other materials which are hydrolyzed by an alkaline solution may be employed as the inner protective film, provided said materials retain their film-forming properties and are not rendered permeable to the liquid composition by said hydrolysis. Examples of hydrolyzable plastics which may be used are polymeric esters such as cellulose acetate, cellulose acetate butyrate, and vinyl acetate.

It will be apparent that alternative forms of containers and of arrangement thereof with respect to a carrier material may be provided within the scope of the invention. Said modifications may, for example, comprise a liquid-carrying portion of a container having either a greater or lesser transverse or longitudinal dimension than the containers shown, or said modified container may have separable marginal surface portions for releasing the contained liquid which vary from the straight linear portions illustrated. It is further to be understood that liquid-carrying containers of the general form illustrated are adapted to introduction to the aforesaid film and print-carrier material from a source of supply separate therefrom as, for example, from a magazine which may releasably retain said containers out of contact with said materials, said magazine having associated means for predeterminedly dispensing said containers between portions of said materials. Where said dispensable method of providing operational assembly of containers with film and print-carrier materials is employed, said containers may be strengthened by a more rigid backing material, as required, and attachment of said containers to either of said materials by adhesive means may be obviated.

Since certain changes may be made in the above products and different embodiments of the invention could be made without departing from the scope thereof, it is intended that all matter contained in the above description or shown in the accompanying drawings shall be interpreted as illustrative and not in a limiting sense.

What is claimed is:

1. A product capable of directly dispensing a processing liquid in a relatively uniform layer over the interface area of a pair of superposed elements when squeezed between said elements by a pair of pressure-applying members, said product comprising a rupturable disposable container having a pair of opposed walls secured together to provide a liquid-containing cavity, said cavity holding a highly alkaline processing liquid, each of said walls being formed of a sheet material comprising a plurality of layers and at least one of said walls being flexible and deformable for transmitting pressure applied to the exterior of the container directly to the container contents, the internal layer of each said wall being a film of resin substantially impervious to the alkaline liquid in the cavity and inert to said liquid, another of the layers of each said wall, separated from the container contents by said film of resin, being substantially vapor impervious and comprising a metallic foil susceptible to chemical attack by direct contact with alkaline liquids, marginal portions of said walls being adhesively secured together in face-to-face relation to provide a plurality of closures for said cavity, said closures being formed at least in part by directly bonding together the resin films of said walls, one of said closures parallel-

ing said cavity being substantially weaker than the remaining closures, whereby the application of pressure to the exterior of said container causes said one closure to rupture prior to the others and form a liquid-dispensing passage providing for the direct discharge of the liquid from the container over an area substantially as wide as said one closure, each of said opposed walls extending continuously, without folds, throughout its liquid-confining area and the area of said closures.

2. The product of claim 1 wherein the principal constituent of the resin film is a polyvinyl acetal and the metallic foil is a lead foil.

3. A product capable of directly dispensing a processing liquid in a relatively uniform layer over the interface area of a pair of superposed elements when squeezed between said elements by a pair of pressure-applying members, said product comprising a rupturable disposable container having a pair of opposed walls secured together to provide a liquid-containing cavity, said cavity holding a highly alkaline processing liquid, each of said walls being formed of a sheet material comprising a plurality of layers and at least one of said walls being flexible and deformable for transmitting pressure applied to the exterior of the container directly to the container contents, the internal layer of each said wall being a film of resin substantially impervious to the alkaline liquid in the cavity and inert to said liquid, another of the layers of each said wall, separated from the container contents by said film of resin, being substantially vapor impervious and comprising a metallic foil susceptible to chemical attack by direct contact with alkaline liquids, marginal portions of said walls being adhesively secured together in face-to-face relation to provide a plurality of closures for said cavity, said closures being formed at least in part by directly bonding together the resin films of said walls, one of said closures paralleling said cavity being substantially weaker than the remaining closures, whereby the application of pressure to the exterior of said container causes said one closure to rupture prior to the others and form a liquid-dispensing passage providing for the direct discharge of the liquid from the container over an area substantially as wide as said one closure, each of said opposed walls extending continuously, without folds, throughout its liquid-confining area and the area of said closures, each of said pair of opposed walls of said container being one fold of a single integral blank of said sheet material.

4. A product capable of directly dispensing a processing liquid in a relatively uniform layer over the interface area of a pair of superposed elements when squeezed between said elements by a pair of pressure-applying members, said product comprising a rupturable disposable container having a pair of opposed walls secured together to provide a liquid-containing cavity, said cavity holding a highly alkaline processing liquid, each of said walls being formed of a sheet material comprising a plurality of layers and at least one of said walls being flexible and deformable for transmitting pressure applied to the exterior of the container directly to the container contents, the internal layer of each said wall being a film of resin substantially impervious to the alkaline liquid in the cavity and inert to said liquid, another of the layers of each said wall, separated from the container contents by said film of resin, being substantially vapor im-

pervious and comprising a metallic foil susceptible to chemical attack by direct contact with alkaline liquids, marginal portions of said walls being adhesively secured together in face-to-face relation to provide a plurality of closures for said cavity, said closures being formed at least in part by directly bonding together the resin films of said walls, one of said closures paralleling said cavity being substantially weaker than the remaining closures, whereby the application of pressure to the exterior of said container causes said one closure to rupture prior to the others and form a liquid-dispensing passage providing for the direct discharge of the liquid from the container over an area substantially as wide as said one closure, each of said opposed walls extending continuously, without folds, throughout its liquid-confining area and the area of said closures, each of said pair of opposed walls of said container being one fold of a single integral blank of said sheet material, and said blank being folded along a line which extends in the direction of the long dimension of the liquid-containing cavity, the latter being elongated and said one closure paralleling its length.

5. A product capable of directly dispensing a processing liquid in a relatively uniform layer over the interface area of a pair of superposed elements when squeezed between said elements by a pair of pressure-applying members, said product comprising a rupturable disposable container having a pair of opposed walls secured together to provide a liquid-containing cavity, said cavity holding a highly alkaline processing liquid, each of said walls being formed of a sheet material comprising a plurality of layers and at least one of said walls being flexible and deformable for transmitting pressure applied to the exterior of the container directly to the container contents, the internal layer of each said wall being a film of resin substantially impervious to the alkaline liquid in the cavity and inert to said liquid, another of the layers of each said wall, separated from the container contents by said film of resin, being substantially vapor impervious and comprising a metallic foil susceptible to chemical attack by direct contact with alkaline liquids, marginal portions of said walls being adhesively secured together in face-to-face relation to provide a plurality of closures for said cavity, said closures being formed at least in part by directly bonding together the resin films of said walls, one of said closures paralleling said cavity being substantially weaker than the remaining closures, whereby the application of pressure to the exterior of said container causes said one closure to rupture prior to the others and form a liquid-dispensing passage providing for the direct discharge of the liquid from the container over an area substantially as wide as said one closure, each of said opposed walls extending continuously, without folds, throughout its liquid-confining area and the area of said closures, said opposed walls being separate blanks of said sheet material.
